(57) **CLAIM**

(21) Appl. No.: **29/753,908**

The ornamental design for a battery compartment cover with power connector hole, as shown and described.

(22) Filed: **Oct. 3, 2020**

DESCRIPTION

(51) LOC (14) Cl. 13-03

FIG. 1 is a front view of the battery compartment cover with power connector hole, showing my new design;

(52) U.S. Cl.

FIG. 2 is a top view thereof;

USPC **D13/156**

FIG. 3 is a left side view thereof; the right side view is a
